UNITED STATES PATENT OFFICE.

PAUL W. VANDENHOFF, OF CHICAGO, ILLINOIS.

WINDOW-SHADE COVER.

SPECIFICATION forming part of Letters Patent No. 660,473, dated October 23, 1900.

Application filed October 6, 1899. Serial No. 732,805. (No model.)

To all whom it may concern:

Be it known that I, PAUL W. VANDENHOFF, a citizen of the United States, residing at Chicago, Illinois, have invented certain new and 5 useful Improvements in Window-Shade Covers, of which the following is a specification.

The object of my invention is to make a cover or case to protect window-shades from becoming dirty and discolored where exposed 10 on the spring-roll; and my invention consists in the features and details of construction hereinafter described and claimed.

In the drawings, Figure 1 is a front elevation, partly in section, showing the application 15 of my improved window-shade cover; Fig. 2, a transverse section taken in the line 2 of Fig. 1, and Fig. 3 is an end view of the cover.

As is well known, window-shades become 20 soiled with dust and dirt, particularly at the point immediately above the roller, so that when they are drawn down there will be a soiled or dirty streak across the shade at that point. If a shade be left up or partially up 25 for a few days, the dust and grime that will settle on it immediately above the roller will be very noticeable when it is again drawn down. Furthermore, the shade is seldom entirely rolled up around the roller when in its 30 up condition, but usually a few inches is left hanging down. When the shade is lowered, this soiled and discolored strip will mar and even spoil the appearance of the shade. These results are particularly noticeable on 35 light-colored shades and shades of the better quality. It is to obviate this deterioration and injury from the accumulation and settlement of dust and grime that my invention is made.

40 In making my improved window-shade cover I make a cover A of any desired material—as, for instance, tin, papier-mâché, wood-pulp, or other light material which can easily be formed into the desired shape. Of course 45 it will be understood that the cover will be finished by painting or otherwise, so that it will present any desired color and appearance. The cover is provided at its lower edge with a lip a and preferably two of them, between 50 which the window-shade is intended to be drawn out or allowed to pass through as it is

being wound up on the roller. I provide caps or end pieces B for the cover, made of the desired size, to fit over and be retained upon the ends, and provide them with holes to permit 55 the rods or pintles on the ends of the roller to pass through the caps and be received into their usual brackets or supports. No other means are provided for supporting the cover. It rests upon and is carried by the rods or 60 pintles by which the shade-roller is held in place. It is desirable that the lips of the cover should always depend or hang down, as shown in the drawings. To this end I may arrange the hole b slightly eccentric or nearer 65 the top of the caps or end pieces, so that the weight of the covers will be on the underside. This insures the proper positioning of the opening in the cover without having to depend upon the shade itself to hold it in position, or if it is preferred to have the holes in 70 the caps arranged at their axial centers then the proper positioning of the opening in the cover and the downward position of the lips can be obtained by making an angular opening in the cap at that end of the roller in 75 which the rod or pinte is made angular to fit its support or bracket. As is well known, one of the rods or pintles is always made angular in form to be received into an angular 80 recess in its support or bracket, and the hole in the cap at this end may be made of corresponding angular form, as shown in Fig. 3. I also prefer to make the opening between 85 the lips sufficiently narrow to prevent the lower bar or stick of the window-shade from passing between them. In this way they will always prevent the shade from being unwound by the spring-roller carrying its end up and around it, as frequently happens, a 90 number of times. I also prefer to have the rear lip—the one nearest the window—depend in substantially a right line or with much less inclination than the front lip, as shown 95 in Fig. 2.

In assembling the parts the shade is mounted on the spring-roller in the usual way. One of the caps or end pieces is removed—is made removable for the purpose—and the spring-roller, with the curtain-roll put on it to the 100 point desired, is slid into the cover through the end with the shade protruding out through

the opening between the lips. The rod or pindle on the end of the roller first inserted passes through the cap or end piece left on the cover, and the cap or end piece, taken off to permit the insertion of the roller, is then placed on or applied in place of the pindle at that end of the roller, the roller being passed through the hole in the cap, the cover thus being secured to the brackets.

on which to mount and hold the cover around the roller, substantially as described.

3. A window-shade cover provided with a cap or head.
